(57) CLAIM

The ornamental design for a kitchen furniture assembly, as shown and described.

DESCRIPTION

FIG. 1 is a perspective view of the ornamental design for a kitchen furniture assembly according to the present invention;

FIG. 2 is a perspective view of the ornamental design for a kitchen furniture assembly according to FIG. 1 with the central island shown in phantom removed for clarity;

FIG. 3 is a left side plan view of the ornamental design for the kitchen furniture assembly as shown in FIG. 1; and,

The broken line showing environmental structure is included for the purpose of illustrating a portion of the claim that forms no part of the claimed design.

1 Claim, 4 Drawing Sheets
